UNITED STATES PATENT OFFICE.

JAMES M. BALDWIN, OF BROWNVILLE, NEW YORK; MARY R. BALDWIN ADMINISTRATRIX OF SAID JAMES M. BALDWIN, DECEASED.

STEAM DRIER.

Application filed April 7, 1922. Serial No. 550,310.

To all whom it may concern:

Be it known that I, JAMES M. BALDWIN, a citizen of the United States, residing at Brownville, in the county of Jefferson, 5 State of New York, have invented certain new and useful Improvements in Steam Driers; and I do hereby declare the following to be a full, clear, and exact description of the invention, such as will enable others 10 skilled in the art to which it appertains, to make and use the same.

In paper manufacture, when the paper web leaves the felts or presses of the forming machine it still contains some 65% or 15 more of water, the bulk of which is removed by passing the paper through a battery of rotating drying cylinders. These cylinders are steam heated. In order to utilize efficiently the heat of the steam it should, of 20 course, be condensed within the cylinders, and not merely passed through them in gaseous form. Thus arises the problem of removing the condensate and inert gasses from the rotating cylinders, for it is clear 25 that a cylinder half filled with water is not only inefficient as a drying instrument, but requires unnecessary power for its rotation.

The system most commonly employed for removing this condensate involves the use 30 of siphons. A pipe enters each drier through one of its trunnions, and bends down to within an inch or so of the lowest line of the cylinder. Its other end is connected to a common drip header situated below the level of the cylinders and sealed by 35 a water trap from the atmosphere. Steam from a common header is introduced to the cylinders likewise through one of the trunnions, ordinarily the same one through which 40 the siphon pipe passes. In starting the drier in operation, most of the steam passing into the cold cylinders will condense there until after a time the condensate will rise and cover the inner ends of the exhaust siphons. If the pressure differential 45 between the cylinders and the drip header is sufficient this condensate will be forced up the siphon pipes through the trunnions and down until a siphoning action is set 50 up and the cylinders emptied. At first the pressure within the drip header is low and this necessary differential exists. Gradually, however, as the system warms up the pressure within the drip header rises and 55 the pressure differential between the cylinders and the drip header drops, due to the fact that in normal operation steam is always freely passing from some of the cylinders into the drip header, and this being open to all the cylinders distributes the 60 pressure. As a result the differential is not enough to lift the condensate the distance between the trunnion and the level of the condensated water in the cylinders—about 18 inches. Thus we see that the siphon operation cannot be initiated until the pressure differential is sufficient to raise the condensate from its level in the cylinder to the trunnion and force it down the other leg of the siphon far enough to start the 70 siphon action, and that in the nature of things this differential must be small. What is the result? The condensed water accumulates in many of the cylinders until they are almost half filled, or until, by its 75 own condensation, it raises its level to such a point that the slight pressure within the cylinder is sufficient to start the siphon action.

It is also to be noted that the system 80 makes no provision for the elimination of entrapped air. The cylinders are originally filled with air and the steam brings some air with it. The steam condenses and is removed, but the air does not condense and 85 remains. It remains in the system and gradually cuts down the amount of steam which can enter. As less steam enters the cylinders they become less effective. Besides, as less steam enters less steam is condensed, and the level of the condensate approaches the effective siphon level more and more slowly. Finally it gives up the attempt and the air-bound cylinders almost 90 half filled with water turn merrily on, cold and dead, consuming power to no good. In a battery of 72 drying cylinders it is common to find from 6 to 10 in this condition. Under the circumstances there is just one 95 thing to do—blow the battery out. High 100 pressure steam is turned on and the whole battery emptied of its water. This is heroic treatment and indicates that something is wrong with the system which requires it.

To recapitulate then, we see that the present siphon system for removing the condensate is inefficient. It permits the cylinders to half fill with water before they are emptied. It provides no automatic means for eliminating air and so after a time the 110

cylinders become dead and air-bound. It is the object of the present invention to reduce these inefficiencies to a minimum.

Now when the siphon acts it draws over 5 all of the water in the cylinder above the level of its end, and the siphon pipe then fills with steam mixed with a little air. When this steam condenses it reduces the pressure within the siphon pipe. Ordinarily this is automatically taken up by 10 the back pressure steam from the drip header which in present practice is always in open communication with some empty cylinders. It occurred to me that if each 15 siphon were automatically cut off from the drip header after each emptying, and sealed, after a while this drop in pressure, due to condensation, would establish a sufficient pressure differential to initiate the 20 siphon action. And besides each cylinder would be acting independently of every other cylinder. As a simple and satisfactory method of effecting this seal, I lead the 25 down-coming siphon pipe into the drip header, not through its top, as is customary, but through its bottom, after first making a U bend. As the drip header is always 30 partly filled with water (or can be made so by slightly inclining the end which enters the trap), the U-bend of each siphon will also be filled with water. I also provide means through which the air entrapped 35 in the siphon pipe can be forced out. This is preferably a thermostatic air valve.

35 The invention will be more clearly understood after a study of the accompanying drawing which discloses a preferred embodiment of it, although other arrangements of the parts might be made to operate in accordance with the principles discussed above. In this drawing the single figure represents 40 a vertical section through a battery of drying cylinders showing one end of an upper cylinder and some of the connections in section, and one end of a lower cylinder and its connections in elevation. The general arrangement of these cylinders, the method of driving them and supplying steam to them is well understood and, as it forms no part 45 of the present invention, will be described only very briefly.

In this drawing 1 represents the drying cylinders provided with hollow trunnions 2 journaled at 3 upon standards 4 and driven 50 by means of intermeshing gear wheels 5. Steam is supplied from any suitable source 55 through a steam header 6, from which it passes through vertical pipes 7 to each individual drier passing through the hollow trunnions 2. The condensate which forms 60 in the bottom of each cylinder is removed through a siphon pipe 8 which extends from a point near the bottom of the cylinder, through the center of a hollow trunnion, and 65 into a vertical extension 9 which leads di-

rectly to the drip header 10. According to present practice this extension 9 of the siphon is led into the upper side of the drip header.

According to the present invention the 70 lower end of pipe 9 is bent to form a U 11 and enters the drip header through its bottom. As stated before, the drip header is constructed so as to be partly filled with water, and this, of course, flows into the U- 75 bend 11 and seals the lower end of the pipe 9, as clearly shown in the drawing.

The only other change contemplated by the present invention is the provision of a 80 thermostatic air valve 12 situated at the upper end of pipe 9 and the outer end of pipe 8, that is, at the bend of the siphon.

The operation of the driers when modified in accordance with the present invention is as follows: Steam is introduced into the cylinders 1 from the steam header 6 and, the cylinders being cold the steam condenses 85 within them. The condensate collects in the bottom of the cylinder and gradually extends above the lower end of the siphon pipe 9. As the cylinder warms up the steam pressure rises to a point where it is sufficient to force the condensate up the pipe 8 through the trunnion and down the pipe 9 far enough to 90 initiate a siphoning action. The cylinder is then immediately emptied of its water. As the last water passes over the siphon, pipe 8-9 becomes filled with steam mixed with a 95 little air under the steam pressure of the cylinder. Gradually a second volume of condensate forms and seals the lower end of the pipe 8. The entrapped steam in pipe 8-9 gradually condenses and thus reduces the pressure within the siphon. In response to 100 this decrease in pressure a column of water rises in pipe 8 and a second column from the U-bend 11 in pipe 9. Any air within the siphon pipe is forced out through the thermostatic air valve 12 by pressure from cylinder 110 and drip header; condensate from the cylinder is forced over and the siphon action is again set up. This operation is repeated 115 indefinitely.

Thus by the simple expedient of sealing the lower end of the siphon pipe and providing an air valve within it, it becomes unnecessary to wait until each cylinder is half filled with water before the siphoning action can begin. This action is automatically 120 set up through the reduced pressure in the siphon pipe from either condensation of entrapped steam or the escape of air through valve No. 12 long before the cylinder has half filled with condensate. There is also 125 no danger that the cylinder will become air-bound, for with each siphoning action some of the air is carried over into the siphon pipe and expelled through valve 12 before the 130 next siphoning action.

I claim:

1. A steam drier comprising the combination of a rotary drying cylinder, means for introducing steam thereinto, a hollow trunnion, a siphon pipe for removing the condensate passing upwardly from a point near the bottom of the cylinder, through the trunnion and then bending downwardly, said siphon pipe being provided at its outer end 10 with a water seal, and an air valve at the bend of the siphon.

2. A steam drier comprising the combination of a rotary drying cylinder, means for introducing steam thereinto, a hollow trun-

nion, a drip header for receiving the condensate from the cylinder, a siphon pipe for removing the condensate from the cylinder to the drip header passing upwardly from a point near the bottom of the cylinder, through the trunnion and then bending 20 downwardly to the drip header, the lower end of the siphon pipe terminating in a U-bend and entering the drip header from below, and a thermostatic air valve at the bend of the siphon.

In testimony whereof I affix my signature.

JAMES M. BALDWIN.
